[57] CLAIM

The ornamental design for UDU drum holder, as shown and described.

DESCRIPTION

FIG. 1 is a top plan view of a UDU drum holder showing my new design;

FIG. 2 is a front elevational view thereof;

FIG. 3 is a side elevational view thereof;

FIG. 4 is a front perspective view thereof; and,

FIG. 5 is a rear perspective view thereof.

The broken line showing of an UDU drum and support legs is for illustrative purposes only and forms no part of the claimed design.

FIG. 3

FIG. 1

FIG. 2

FIG. 5

FIG. 4
